UNITED STATES PATENT OFFICE.

JAMES B. JOHNSTON AND CLARENCE B. LITTLE, OF DAYTON, OHIO.

DESIGN FOR A WATER-TUBE BOILER.

SPECIFICATION forming part of Design No. 28,122, dated January 4, 1898.

Application filed November 22, 1897. Serial No. 659,525. Term of patent 7 years.

To all whom it may concern:

Be it known that we, JAMES B. JOHNSTON and CLARENCE B. LITTLE, citizens of the United States, residing at Dayton, in the county of Montgomery and State of Ohio, have invented and produced a new and original Design for a Water-Tube Boiler; and we do declare the following to be a full, clear, and exact description of the same, reference being had to the accompanying drawings, forming a part thereof.

Figure 1 is a front elevation of a water-tube boiler showing our specific design. Fig. 2 is a side elevation of the same. Fig. 3 is a reduced plan view of the same.

As is amply illustrated in the drawings, the features that are leading or material in the design consist of a circular boiler A, a rectangular flange-plate B, with upwardly-projecting annular collar c, that embraces a central part of the boiler, and a dome consisting of an upper concave plate D, conforming to the rounded shape of the boiler, and a bottom concave plate E, identical in form with the

upper plate D. The rectangular flange-plate B has a concentric row of circular holes a disposed inwardly adjacent to the side of the boiler, as shown in Fig. 3. The bottom concave plate E has a concentric row of water-tubes F disposed radially therefrom on angles 30 to the vertical center of the boiler and graduated in lengths, substantially as is shown in Figs. 1 and 2, the said water-tubes having the shortest lengths being in the front portion of the plate E.

Having described our invention, what we claim as new, and desire to secure by Letters Patent, is—

The design for a water-tube boiler as herein shown and described.

In testimony whereof we affix our signatures in presence of two witnesses.

JAMES B. JOHNSTON.
CLARENCE B. LITTLE.
